CLAIM

The ornamental design for a LED lamp, as shown and described.

DESCRIPTION

FIG. 1 is a top and side perspective view of a first embodiment of an LED lamp showing our new design;

FIG. 2 is a side elevational view thereof;

FIG. 3 is a top and side perspective view of a second embodiment of an LED lamp showing our new design;

FIG. 4 is a side elevational view thereof;

FIG. 5 is a top and side perspective view of a third embodiment of an LED lamp showing our new design;

FIG. 6 is a side elevational view thereof;

FIG. 7 is a top and side perspective view of a fourth embodiment of an LED lamp showing our new design; and,

FIG. 8 is a side elevational view thereof.

The broken line showing is included for the purpose of illustrating only and forms no part of the claimed design.

The articles depicted in the figures are surfaces of revolution.

In FIGS. 5-8, the darker stippling on the annular peripheral region on the upwardly-facing lamp surface denotes a color different from that of the upwardly-facing central region, and the darker stippling on the lower lamp surfaces denotes a color different from both the annular peripheral region of the upwardly-facing lamp surface and the central region of the upwardly-facing lamp surface. In particularly preferred embodiments, the color of the annular peripheral region of the upwardly-facing lamp surface is red and the color of the depicted lower lamp surfaces is blue, green, purple or yellow, although different colors may be used for each of these regions.
